GAS STOVE.

No. 19,700.

Patented Mar. 18, 1890

UNITED STATES PATENT OFFICE.

CHARLES F. ADAMS AND ARTHUR W. RIVETT, OF CHICAGO, ILLINOIS,
ASSIGNORS TO THE CHICAGO GAS STOVE COMPANY, OF SAME PLACE.

DESIGN FOR A GAS-STOVE.

SPECIFICATION forming part of Design No. 19,700, dated March 18, 1890.

Application filed January 10, 1890. Serial No. 336,595. Term of patent 7 years.

To all whom it may concern:

Be it known that we, CHARLES F. ADAMS and ARTHUR W. RIVETT, citizens of the United States, residing at Chicago, in the county of Cook and State of Illinois, have invented a certain new and useful Design for a Stove for Burning Gas, of which the following is a specification, reference being had therein to the accompanying drawing.

10 This design consists in the peculiar ornamentation and form of a stove designed for use in burning gas as fuel, and is shown in the accompanying photographs in perspective view.

15 The stove consists of a low base-section composed of legs with an ornamental border between and the molding surmounting the legs. On an ornamental section upon this base is supported a four-sided prismatic body with 20 the sides provided with ornamental panels with the corners rounded off. The front side is provided with a rectangular opening, which extends from near the bottom to near the top

of the stove, and is surrounded by an ornamental border. Below this opening is an ornamental hood in the form of a quarter-roll, provided with a single ornamental panel. Above the opening or fire-place is a similar hood having as ornamental features two medallions. Supported upon the body already 25 described is a dome-shaped top, the upper portion of which is in imitation of a cover and is surmounted by a bronze or other statuette, such as the horse shown in the photograph.

30 What we claim is—

35 The design for a gas-stove, substantially as shown and described.

In testimony whereof we affix our signatures, in presence of two witnesses, this 28th 40 day of December, 1889.

CHARLES F. ADAMS.
ARTHUR W. RIVETT.
